Primary Examiner — Omeed Agilee(74) *Attorney, Agent, or Firm* — Womble Bond Dickinson (US) LLP(57) **CLAIM**

The ornamental design for a carton, as shown and described.

DESCRIPTION

The disclosure of U.S. Provisional Patent Application No. 62/937,960, filed on Nov. 20, 2019, is hereby incorporated by reference for all purposes as if presented herein in its entirety.

FIG. 1 is a front perspective view of a carton showing my new design in a first configuration.

FIG. 2 is a front elevation view of the carton of FIG. 1.

FIG. 3 is a rear elevation view of the carton of FIG. 1.

FIG. 4 is a left elevation view of the carton of FIG. 1, the right elevation view is a mirror image.

FIG. 5 is a top plan view of the carton of FIG. 1.

FIG. 6 is a bottom plan view of the carton of FIG. 1.

FIG. 7 is a left perspective view of the carton of FIG. 1 in a second configuration, the right perspective view is a mirror image; and,

FIG. 8 is a plan view of the carton of FIG. 1 in an unfolded configuration.

The broken lines in the drawings depict portions of the carton that form no part of the claimed design.
